Primary Examiner — Sheryl Lane*Assistant Examiner* — Leisha N Price(74) *Attorney, Agent, or Firm* — Alan D. Kamrath; Karin L. Williams; Mayer & Williams PC(57) **CLAIM**

The ornamental design for extendable lockable pliers, as shown.

DESCRIPTION

FIG. 1 is a perspective view of extendable lockable pliers showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.
